ARMING LOCKING DEVICE FOR A FUZE

Charles F. Bild, Albuquerque, N. Mex., assignor to the United States of America as represented by the Secretary of the Navy

Filed Jan. 23, 1952, Ser. No. 267,903

6 Claims. (Cl. 102—70)

(Granted under Title 35, U.S. Code (1952), sec. 266)

The present invention relates to a fuze and more particularly to an arming locking device for a fuze which is adapted to prevent premature arming.

Heretofore, fuzes have been armed by centrifugal force caused by the spin of the projectile or by means of the set back force due to inertia as the missile is fired from the gun or by a combination of these forces. Many of these arming devices are not adaptable to the newly developed low spinning projectiles. Furthermore such fuzes are more likely to be armed by accidental drop than the fuze presently disclosed.

The present invention may be used in many types of fuzes. It is shown herein as used with a gas pressure operated fuze. A rotor is provided with a detonator which in the armed position is aligned with a primer and lead-in charge. This rotor is provided with a tooth which engages a groove in a pressure operated slideable member. Also engaging in this groove is a pin which is spring biased to a retracted position. This pin is held in the operative position by means of an elongated rack member which is spring urged to an engaged position with the pin. The teeth on this member are engaged by a rotatable gear. Upon set back this elongated rack is retracted from an engaged position with the pin and, when in the completely withdrawn position, enlarged teeth on the elongated rack engage the gear, causing the rack to be forced to an inoperative position. The spring biased pin is then released for movement to the retracted position out of engagement with the pressure responsive member. A gas generating device initiated by any suitable means such as a set back operated switch is set off causing the slideable member to be forced forward in the bore thereby rotating the rotor to align the detonator with the primer and lead-in charge. The essence of the invention resides in the provision of the elongated rack with enlarged teeth and the gear wheel which adds sufficient weight to the unlocking means to prevent the arming of the fuze by accidental drop. It will be seen that the set back force must be of such duration that the rack member will not only compress the spring but will also overcome the inertia of the gear wheel.

The primary object of the present invention is the provision of an arming device for a fuze particularly adapted for use with a low spinning projectile.

A further object of this invention is to provide an arming device for a fuze which will distinguish between the set back resulting from an accidental drop and that caused by the missile being fired.

An additional object of the invention is the provision of an inertia wheel in an arming device which will add sufficient weight to the unlocking means to prevent the arming of the fuze by accidental drop.

A still further object of this invention is the provision of an arming device for a fuze having a rack with enlarged teeth as a locking means for a spring pressed pin whereby upon withdrawal of the rack member the enlarged teeth engage a gear thereby shifting the rack to

2

an inoperative position and preventing reengagement of the rack with the spring pressed pin.

Other objects and many of the attendant advantages of this invention will be readily appreciated as the same becomes better understood by reference to the following detailed description when considered in connection with the accompanying drawings wherein:

Fig. 1 is a view of the fuze in elevation;

Fig. 2 is an enlarged sectional view taken along the line 2—2 of Fig. 1;

Fig. 3 is a sectional view taken along the line 3—3 of Fig. 2;

Fig. 4 is a view similar to Fig. 2 showing the fuze in armed position;

Fig. 5 is a sectional view taken along the line 5—5 of Fig. 4; and

Fig. 6 is a sectional view taken along the line 6—6 of Fig. 5.

Referring now particularly to Fig. 1 there is shown a fuze composed of sections 1, 2, 3 and 4 which are detachably secured together in any suitable manner as, for example, by means of studs 5 and 6 (Fig. 2) press fitted in cover plate 1, center sections 2 and 3, and lower section 4.

Within lower section 4 there is provided a bore 7 having a screw threaded cap 8 which may be removed in order to insert slideable plunger 9. This plunger is provided with a flared end portion 11 which seats in a similarly flared portion in bore 7. The opposite end portion of plunger 9 is provided with a central screw threaded aperture to receive a threaded end section 12 having a circumferential groove 13.

Within lower section 4 of the fuze body is further provided a circular recess 14 within which is rotatably mounted on shaft 15 a rotor 16 having a portion thereof cut away as at 17 and a tooth 18 which is adapted to be received within groove 13 of end section 12. Rotor 16 is further provided with a chamfered section on the lower surface thereof at 19 and a port 21. Port 21 is adapted to receive a detonator which in the armed position of the rotor is aligned with a lead-in charge located within a port 22 in the bottom section 4 beneath rotor 16 and a primer (not shown) which is located in section 3 in alignment with port 22. Within recess 14 is fixedly mounted a stop pin 23 which limits the rotational movement of rotor 16. A spring 24 suitably secured in section 4 of the fuze body is adapted to coact with a notched portion 25 of the rotor to retain the rotor in the armed position.

Provided in section 4 adjacent bore 7 is a port 26 having a connecting channel 27 with the bore. This port is adapted to contain a gas generating device actuated by any suitable means such as an inertia switch located in a port 28. The details of construction of the gas generating device and actuating means therefor form no part of the present invention and may be of any well known variety. For example in the application of Robert O. Wynn for a Combination Fuze for a Bomb, Serial No. 748,328, filed May 15, 1947, now Patent No. 2,754,760, is disclosed a gas generating device and detonator therefor which could be adapted for use in the present invention.

Located within section 4 of the fuze body is a bore 29 in which is provided a headed locking pin 31. This bore communicates with bore 7 through a reduced aperture 32. The locking pin 31 is adapted to engage groove 13 in head portion 12 of plunger 9 to lock the plunger in the position shown in Fig. 2. Locking pin 31 is urged to a retracted position by a compression spring 33 which acts between the shoulder formed by the reduced aperture 32 and the head of locking pin 31. The outer end of

bore 29 is closed by means of cap 34 which is pressed in the bore after insertion of the locking pin.

In Fig. 3 is disclosed the means for retaining locking pin 31 in engagement with groove 13 of the slideable plunger. There is provided a hollow portion 35 within sections 3 and 4 having a reduced aperture 36 in one end thereof communicating with bore 29. Within section 2 of the fuze body is a bore 37 of smaller diameter than hollow portion 35 and communicating therewith is an aperture 38 in cover plate 1. Slidably disposed within aperture 36, hollow portion 35 and bore 37 is a rack 39 having teeth 41 some of which are enlarged as at 42. A compression spring 43 is provided which acts between the shoulder formed by cover plate 1 surrounding aperture 38 and a tooth 41 and this spring urges rack 39 through aperture 36 thereby extending into engagement with locking pin 31 to retain this pin within groove 13 of the slideable plunger 9.

Within hollow portion 35 there is rotatably mounted a gear 44 (Fig. 6) the teeth of which mesh with teeth 41 on the rack member 39. This gear is made of a material chosen so that the weight of the gear is sufficient to add enough inertia to the rack member to prevent complete withdrawal of the rack from engagement with the locking pin except under conditions of sustained setback force incurred only upon firing.

The operation of the device is as follows. Upon firing a projectile containing the disclosed fuze the parts will be in the position shown in Fig. 2. The set back force due to inertia will cause rack member 39 to be withdrawn from engagement with locking pin 31 through aperture 36. In so doing the rack overcomes both the resistance offered by spring 43 and the inertia of gear 44. When the rack member is completely withdrawn through aperture 36, the enlarged teeth 42 engage the gear wheel causing the rack member to shift to the position shown in Fig. 5. It will be seen that after the rack member has been so shifted it is prevented from reentering aperture 36 both by the spring 43 which forces the rack member against the shoulder surrounding aperture 36 and by the engagement of gear 44 with the enlarged teeth. When the rack member is withdrawn from engagement with locking pin 31, spring 33 forces this pin to a retracted position out of engagement with slideable plunger 9.

Substantially simultaneously with retraction of this locking pin the gas generating device located in port 26 is actuated thereby generating pressure behind the slideable plunger 9. Upon creation of sufficient pressure plunger 9 is thrust forward thereby bending flange 11 inwardly. This thrust is imparted to rotor 16 through tooth 18 and the rotor rotates to the position shown in Fig. 4 in response thereto. The tooth engages the plunger for only approximately 30° of the total 80° movement of the rotor, the plunger imparting sufficient momentum to the rotor for rotation for the remaining 50°.

The rotor is stopped in the position of alignment of the detonator and the lead-in charge by the engagement of the stop pin 23 with the cut away portion 17 of the rotor. Spring 24 engages notch 25 to prevent counterclockwise movement of the rotor which is thereby effectively held in the armed position.

It is seen therefore that a locking means has been provided which will prevent any movement of the plunger prior to firing. The set back force required to withdraw the rack member must be sustained in order for the rack to overcome the inertia of the gear. The sudden deceleration incurred by an accidental drop will not cause complete withdrawal of the rack member.

Obviously many modifications and variations of the present invention are possible in the light of the above teachings. For example, the enlarged teeth 42 could be replaced by teeth of normal size such as shown at 41 and a spring provided to act between rack member 39 and

the wall of the bore so as to force the rack member out of alignment with aperture 36 when the rack member is in a withdrawn position. In this form the gear 44 serves no other purpose than as an inertia element to add weight to the rack member and prevent premature withdrawal. In either embodiment it should be clear that integration of motion of the rack member on a succession of accidental drops is impossible due to the fact that spring 43 returns the rack member to its initial position after each vibration or accidental drop. It is therefore to be understood that within the scope of the appended claims the invention may be practiced otherwise than as specifically described.

The invention described herein may be manufactured and used by or for the Government of the United States of America for governmental purposes without the payment of any royalties thereon or therefor.

What is claimed as new and desired to be secured by Letters Patent of the United States is:

1. A locking means for a fuze comprising a body having a bore therein and an interconnecting aperture arranged transversely thereto, a spring pressed locking pin slidably mounted in said bore, an elongated rack member extending into engagement with said locking pin through said aperture and normally retaining said locking pin in locking position, a first group of teeth and an enlarged group of teeth disposed on said rack member, and a geared inertia wheel rotatably mounted within said body, said wheel initially meshing with said first group of teeth on said rack member and being normally out of engagement with said enlarged group of teeth, said rack member being withdrawn through said aperture in response to set back force to release the locking pin whereby withdrawal of said rack member positions said enlarged group of teeth to engage said geared inertia wheel thereby shifting said rack member out of alignment with the aperture.

2. A locking means for a projectile fuze comprising a toothed rack member pressed to a locking position by means of a spring and movable to a retracted position by the set back force incurred when the projectile is fired, and a geared inertia wheel initially meshing with a section of teeth on the rack member and proportioned to add sufficient weight to the locking means to prevent substantial movement of the rack member when the set back force is of less than predetermined duration, said rack member having a section of enlarged teeth out of engagement with the geared inertia wheel when the rack member is in a locking position and so positioned that when the rack member is retracted due to set back force said section of enlarged teeth engage said inertia wheel whereby the rack member is shifted out of the line of normal longitudinal movement of the rack member thereby preventing return of the rack member to locking position.

3. In a projectile fuze having a slideable pressure responsive member adapted to actuate a rotor for arming the fuze, a locking means for the slideable member comprising a pin in engagement with the slideable member and spring urged toward retracted position, an elongated toothed rack member disposed along the longitudinal axis of the projectile and normally spring pressed into engagement with said pin for maintaining the pin in the locking position, and a geared inertia wheel meshing with the teeth on the rack member whereby when the rack member is retracted by set back out of engagement with the pin, the pin will be retracted and the pressure responsive member will be released.

4. In an arming device for a fuze having gas generating means and a rotor with a detonator adapted to be aligned with a primer and lead-in charge when armed and a pressure responsive plunger element having toothed engagement with the rotor, a locking means for the plunger element comprising, a locking pin spring urged to retracted position, a toothed rack member pressed into engagement with said pin by means of a spring to retain

said pin in the locking position, a geared inertia wheel meshing with the teeth on the rack member and of sufficient weight to prevent substantial movement of the rack member from a set back force of less than predetermined duration whereby upon initiation of the set back force due to firing the projectile, the rack member will be withdrawn in time delayed relation from engagement with the locking pin and said locking pin will be retracted releasing the pressure responsive plunger which is actuated by the gas generating means for movement to cause rotation of the rotor thereby aligning the detonator with the primer and lead-in charge.

5. A locking means for a projectile fuze comprising a fuze body having a bore therein and an interconnecting aperture arranged transversely thereto, a locking pin slidably mounted in said bore, spring means urging said pin to an unlocking position, a toothed rack member extending into engagement with said locking pin through said aperture and normally retaining said locking pin in a locking position, a geared inertia wheel rotatably mounted within said body and initially meshing with a section of teeth on said rack member, said rack member having an additional section of teeth of greater dedendum than the first mentioned section of teeth and so disposed along the rack member as to engage the geared wheel only when the rack member has been completely withdrawn through said aperture, said additional section of teeth when engaging said geared wheel causing said rack member to move angularly with respect to the normal path of movement of said rack member to a position out of

30

alignment with said aperture to prevent the return of the rack member to the locking position.

6. In a projectile fuze having a slideable pressure responsive member adapted to actuate a rotor for arming the fuze, a locking means for the slideable member comprising a pin in engagement with the slideable member and spring urged toward a retracted position, an elongated member supported for longitudinal movement along a predetermined axis and normally spring pressed into engagement with said pin for maintaining the pin in the locking position, said elongated member being movable to a retracted position by set back force to thereby retract said pin and release said pressure responsive member, motive means mounted contiguous to said elongated member, said elongated member having a first body portion initially engaging said motive means when said elongated member maintains said pin in the locking position and an enlarged body portion positioned to engage said motive means when said elongated member is in the retracted position whereby said elongated member is displaced from said predetermined axis, and arresting means for preventing longitudinal movement of said elongated member when displaced from said predetermined axis.
